Attorney:

UNITED STATES PATENT OFFICE.

ALANSON P. BRUSH, OF DETROIT, MICHIGAN.

MANIFOLD CONSTRUCTION FOR INTERNAL-COMBUSTION ENGINES.

Application filed March 26, 1920. Serial No. 369,151.

To all whom it may concern:

Be it known that I, ALANSON P. BRUSH, a citizen of the United States of America, residing at Detroit, in the county of Wayne 5 and State of Michigan, have invented certain new and useful Improvements in Manifold Constructions for Internal-Combustion Engines, of which the following is a specification, reference being had therein to the 10 accompanying drawings.

It is the object of the invention to obtain a manifold construction in which the liquid fuel which drops out of suspension in the intake will drain into a pocket within 15 the exhaust manifold, where it will be vaporized and returned to the intake. The invention, therefore, consists in the construction and combination of intake and exhaust manifolds as hereinafter set forth.

20 In the drawings:

Figure 1 is a front elevation, partly in section, of the manifolds;

Figure 2 is a vertical central cross-section thereof.

25 A is the exhaust manifold of an internal combustion engine, which is provided with a central depending outlet portion B. C is the intake manifold having the portion thereof adjacent to the carburetor (not shown) arranged in front of the portion B of the exhaust manifold. As shown, this portion D of the intake manifold has an angle-bend E therein and adjacent to this bend an inwardly opening port F, which communicates with an otherwise closed chamber G within the exhaust manifold and preferably formed integral therewith. The arrangement is such that the portion of liquid fuel, which either drops out of suspension 30 or collects on the wall of the intake manifold at the bend therein, will drain downward and into the pocket G, the temperature of which is such that the liquid will be vaporized and will be returned as vapor 35 into the intake.

In the mechanical construction shown the intake manifold is separate from the exhaust manifold and the portion D is clamped to the exhaust manifold by a rod H passing centrally through the pocket G and having 50 threaded opposite ends for engaging the clamping nuts I. By this means the portion D can be firmly clamped to the exhaust manifold, while the gasket J between the two castings will form a gas tight seal. The 55 intake manifold may be of any suitable construction, but as shown the vertical portion K thereof is in the form of a venturi, the effect of which is to thoroughly commingle the ingredients of the explosive mixture 60 before distributing the same to the separate branches leading to the engine cylinders.

What I claim as my invention is:

1. The combination with an exhaust manifold having a central depending outlet portion, of a pocket formed in said outlet portion separate from the exhaust passage with a port opening to the front, an intake manifold having an angling portion with a port adjacent to the angle registering with the 70 port in said pocket, and means for clamping said intake manifold to said exhaust manifold.

2. The combination with an exhaust manifold and an inlet manifold having a horizontal inlet portion, a vertical outlet portion leading therefrom, and an angling portion therebetween, a pocket within said exhaust manifold and extending transversely of said inlet manifold, the bottom of said 80 pocket lying in a horizontal plane only slightly below the horizontal portion of said inlet manifold, and a downwardly sloping passage connecting the angling portion of said intake conduit with said pocket, where 85 by liquid fuel falling out of suspension will drain into said pocket and will be returned as vapor to the intake.

In testimony whereof I affix my signature.
ALANSON P. BRUSH.
